United States Patent Office

Des. 217,601
Patented May 19, 1970

217,601

CHAIR OR SIMILAR ARTICLE

Donald J. Borichevsky, Wells, Vt., assignor to The Telescope Folding Furniture Co., Inc., Granville, N.Y., a corporation of New York

Filed Mar. 12, 1969, Ser. No. 16,208

Term of patent 14 years

Int. Cl. D6—01

U.S. Cl. D15—1

Fig. 1.

FIG. 1 illustrates a front perspective view of a chair according to the invention;

FIG. 2 is an enlarged plan view showing the seat of FIG. 1 in greater detail;

FIG. 3 illustrates a perspective rear view of the chair of FIG. 1;

FIG. 4 illustrates a cross-sectional view taken on line 4-4 of FIG. 1; and

FIG. 5 illustrates an enlarged cross-sectional view of the tubing of multi-sectional construction taken on line 5-5 of FIG. 1.

The chair is characterized by a tubing wherein the tubing is formed of integral multi-sectional construction.

I claim:

The ornamental design for a chair or similar article, as shown and as described.
